FIG. 1

FIG. 2

FIG. 4

FIG. 3

FIG. 5

FIG. 6

FIGURE 1 is a front elevational view of a first embodiment of my design for a portable radio with its retractable handle shown in a carrying position;

FIGURES 2 and 3 are top and right side views respectively, thereof;

FIGURES 4 and 5 are front and rear perspective views thereof with the carrying handle shown in a retracted position; and

FIGURE 6 is a front elevational view of a second embodiment of my design which is identical to the first embodiment except for the particular grille configuration, the omission of the telescopic antenna, and the provision of a single dial scale in place of the two-band dial scale in the first embodiment.

Portions of the drawing are stippled to indicate contrast in appearance.

I claim:

The ornamental design for a portable radio cabinet, substantially as shown and described.
